CLAIM

The ornamental design for a football bottle, as shown and described.

DESCRIPTION

FIG. 1 is a perspective view showing a first embodiment of our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a partial sectional view thereof;

FIG. 9 is a perspective view showing a second embodiment of our new design;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is a partial sectional view thereof.

The broken lines showing environment are for illustrative purposes only and form no part of the claimed design.
